MULTISPOOL REELING MACHINE

Saburo Minorikawa, Koishikawaku, Tokyo, Japan, assignor of one-half to Katakura Seishi Boseki Kabushiki Kaisha, Kyobashi, Kyo-bashiku, Tokyo, Japan

Application December 29, 1938, Serial No. 248,352

12 Claims. (Cl. 19—3)

This invention relates to reeling machine for multiple cocoon thread reeling to be operated by standing operators and has for its object to generally improve the construction of machines of this character to render them more efficient and convenient in operation.

The accompanying drawings show one example of a multi-spool reeling machine according to the present invention.

Fig. 1 is an elevation of the reeling machine. 10 Fig. 2 is its plan.

Fig. 3 is a sectional side elevation.

Fig. 4 is a detail in section of the speed regulating mechanism in the gear box.

Fig. 5 is a detail view taken at right angles to Fig. 4.

Fig. 6 is a perspective view of the working arrangement for creating reciprocating motion of the rocking bar.

Fig. 7 is a side elevation of the spool partly in section.

Fig. 8 is its front elevation.

Fig. 9 is a sectional elevation of the rotary fibre feeding device.

Fig. 10 is a sectional view showing how the cylindrical body is embraced by the embracing bars.

Fig. 11 is a side elevation showing the stopping arrangement of the spools.

Fig. 12 is a plan showing the bent plate of the stopping device.

Fig. 13 is a side elevation partly in section showing the mounting of the rocking bar.

As shown on the drawings, pillars 3 supporting a horizontal beam 2 divide the machine frame 1 into two independent parts, accommodating two separate reeling pan tables 4 and 5. The main axle 6 is horizontally supported by the pillars 3 and on one end of the axle 6, a belt pulley 7 is provided and by means of belt 8 is made to cooperate with pulley 9. One end of the axle 10 of the pulley 9 is introduced into the inside of gear box 11 and is fixed to bevel wheel 12 meshing with a bevel wheel 13 which is fixed to shafting 14.

As shown on Fig. 4 and Fig. 5, a friction ring 15 is loosely fitted to shaft 14; and one edge of the friction ring 15 is engaged with the flat face of wheel 16; the axle 11 of the wheel 16 being supported at both ends by the walls of gear box 11. On one end of axle 11, a spring 18 is provided which tends to press it against friction wheel 16. Underneath axle 14 a threaded rod 19 is provided, one end of which is made to project out to the outside of the gear box 11, and

terminates in a handle 20. On the other end of the rod 19 the bottom portion of bar 21 is screw threaded.

The upper portion of the rod 21 is forked to embrace the shafting 14 between rings 22 and 23 so as to be easily removable, the ring 22 being connected with the friction ring 15.

When the handle 20 is operated and the rod 19 is rotated, the rod 21 moves with it and the friction ring 15 also moves along the shaft 14, thus changing its contact point with wheel 16 and regulating the speed of the wheel 16 accordingly.

On the other end of the axle 11, a worm gear 24 is fixed and a worm gear 25 engaging with it, is fixed to a longitudinal axle 28. A worm gear 28 fixed to spool axle 27 engages the worm gear 25.

Thus, the rotation of axle 14 is transmitted to axle 26 and axle 27; these movements of the axles are independently transmitted to the reeling portions. The other end of axle 27 is simply supported in the gear box 29 of the adjacent reeling machine.

On the other end of shafting 14 a construction similar to that above described is provided and in that way, several multi-spool reeling machines are continuously installed side by side.

To the axle 26, (Fig. 6), a toothed wheel 30 is fixed below the worm gear 25, which wheel is made to engage with another toothed wheel 31. To the axle 32 of toothed wheel 31, a roller 33 is eccentrically fixed and embraced by semi-circular arm pieces fitted on top of an operating axle 34. A sustaining arm 36 at the lower end of the axle 34 is fixed to circular ring 37 to which a circular plate 38 is attached.

The lower portion of the vertical axle 26 is passed through the circular ring 37 and at its lower end, an eccentric plate 39 is fixed. On one side of eccentric plate 39 a pin 40 is fixed and its upper portion is inserted in an oval hole 41 drilled in one side of the circular plate 38.

At the lower portion of and on the other side of the circular plate 38, an arm 42 is fixed, to which a connecting bar 43 is fastened.

The other end of the bar 43 is connected to rocking bar 44.

The rocking bar 44 is provided under the rows of spools and as shown in Fig. 13, both edges 45 are bent into arcuate form and made to be resilient.

A metal line 46 is enclosed by these edges, which latter embrace drum shaped rollers 47 provided in front of the horizontal beam 2.

Thread guides 46 are provided at regular intervals and secured to the bar 44 by brackets 156. Thus, accompanying rotation of the axle 26, the eccentric plate 39 also rotates; and by means of the pin 40, the circular plate 38 rotates, causing the reciprocating motion of rocking bar 44. At the same time, by means of the toothed wheel 30 and the wheel 31 the roller 33 rotates and through the axle 34 the circular plate 38 moves; thus by double action of the eccentric plate 39 and the roller 33, the rocking bar slightly makes sidewise motion simultaneously with longitudinal reciprocating motion.

The above mentioned spool axle 27 is provided on one side of the horizontal beam 2 but on the corresponding other side, an independently working axle 47 is provided and to each of these axles 27 and 47, 15 to 30 spools 48 are attached.

As shown in Fig. 7 and Fig. 8, these spools are frusto-conical shaped and through both end plates 49 and 50, axle holes 51 are formed, through which an axle tube 52 loosely fits. On the ends of the axle tube 52, circular flanges 53 are formed, so as to prevent the tubular axle from slipping off.

On end plates 49 and 50, several reinforcing pieces 54 are formed and at this portion, spools 48 are arranged and regulated in their positions.

Near the inner end of each reinforcing piece 54 projections 55 are formed and prevent the threads detached from spool 48 from winding around the axle 52 and makes it convenient for removing them.

These spools 48 loosely fit on axles 27 and 47 and revolve with the axle by friction.

The spools 48 are constructed of light metal, such as aluminium and coated with corrosion resisting material, so as to make them proof against acid, oil and alkalinity.

Thus, the spools through the thread guides 46 of the rocking bar 44, take up threads coming up from cocoons and wind them.

As shown on Fig. 1, Fig. 2 and Fig. 3, the thread reeling pans 4 and 5 for receiving cocoons, are rectangular-shaped.

In the backward portion of each pan, a water tank 56 is provided and by means of partition wall 57, hollow curved portions 58 and 59 for preserving adjusted cocoons are formed; and on the wall 57 of the hollow curved portion 58 and 59, several projections 60 for hanging threads are formed at intervals. On one side of the hollow curved portion 58 a hollow pot 61 for catching thread ends, is formed and at the same time, proper heating arrangement, such as an injection pipe 62 is provided.

On the other side of the curved basin 58, a fibre adjusting curved basin 63 is formed; and its bottom is connected to the bottom of the fibre end catching basin 61 by a connection pipe 64, a water basin 65 being provided at its middle portion, so as to automatically regulate water levels of the fibre catching and fibre adjusting basins; the bottom of the fibre adjusting basin 63 is connected to the bottom of the water tank 56 by means of a conduit 66 (Fig. 2); and in the fibre catching basin 61 and the fibre adjusting basin 63, a cocoon basket as indicated by 67 and Fig. 1 and Fig. 3 is adapted to be suspended alternately. On one side of other curved hollow pan, a dropped cocoon storage basin 68 is formed and its bottom is drilled with drainage holes 69. On the other side of the

curved hollow pan, boiled cocoon storage basin 70 is provided and drainage holes are formed at its bottom.

The boiled cocoon storage basin 70 and dropped cocoon storage basin 68, are formed within one common wall; and from boiled cocoon storage basin to the edge of dropped cocoon storage basin, the bottom face gradually slopes up, thus making it convenient to take up boiled cocoons for general reeling operation.

On one side of boiled cocoon storage 70 an inferior cocoon storage 72, waste storage 73 and crysalis storage 74 basins are provided side by side; drainage holes 75 being bored at bottom of each basin.

Now to explain the pipe arrangement of the reeling pan, main pipe 76 is horizontally laid in the lower part of machine frame 1 and from the main pipe 76 a connection pipe 77 branches off, which branches again into two separate parts at its upper part, and fitted there with cocks 78 and 79; the outlets 80 and 81 of these pipes, which supply a small amount of water constantly, are turned down into the water tank 56 of reeling pans 4 and 5 provided at both sides of column 3, correspondingly situated.

From the upper part of main pipe 76, connection pipes 82 and 83 branch off and terminate at the fibre end catching basins of reeling pans 4 and 5.

At the ends of these branch pipes, outlets 84 and 85 are fitted so as to be able to turn round freely; and through cocks provided at appropriate situations, a large amount of water may be supplied to the fibre catching pot 61 and the water tank 56, according to the amount needed.

Connection pipes 86 and 87 are fitted to the drainage holes 69 and 71 of dropped cocoon storage 68 and boiled cocoon storage basins 70. Through cocks 88 and 89, these pipes drain into gutters 90 and 91 horizontally laid under reeling pans 4 and 5.

From the gutters 90 and 91 water is drained off, by means of drainage pipes 92 and 93.

Above the water main 76, a steam main pipe 94 is horizontally laid and branches off into pipes 95 and 96; and through valves 97 and 98, these branches are connected to the steam heating pipe 62.

From the bottom of the water tank 56 provided midway between the fibre end catching pot 61 and the fibre adjusting basin 63, a drainage pipe 100 fitted with a cock 99, is connected; its end runs into receiving gutter and drains off water as much as required.

Thus in the reeling pan fitted with steam pipes, water pipes and drainage pipes, fibres from cocoons 101 retained in water tank 56, will go through rotary feeding apparatus, up to spools 48, as will be explained later.

The rotary feeding devices 102 are provided side by side in base plate 103, the number of these devices being the same as that of spools.

As indicated in Fig. 9 and Fig. 10, in each rotary feeding device 102, the upper portion of a thread passage tubular axle 104 passes through the forward edge of a base plate 103, being screw connected thereto, and depending therefrom. An axial hole 106 is drilled through the axle 104 for passage of threads. In the lower portion of the thread passage hole 106, female screw threads are cut, and a flanged body 108 is threaded on the axle 104 and its lower portion is retained in position by the flanged body 108 so as to be

free to revolve. In the rim of the transmission wheel 109, a V-shaped channel is formed; and in the channel, several water holes 111 are bored. These holes communicate with the clearance space 112 provided within transmission wheel 109. The lower part of transmission wheel 109 has a cylindrical shape 113 and around the cylindrical part a groove 114 is cut to receive embracing bars 115 and 116, these bars being fitted so as to be easily detachable.

The embracing bars 115 and 116 consist of two metal members which are bent in their middle portions into semi-circular shape 117 so as to embrace the flanged body; and the straight portions are fastened together by soldering or some other means. In each of the V-shaped grooves 110, a belt 118 is adapted to run. Each belt runs over the grooved pulleys 119 and 120 fitted on both ends of the base plate 103. Each of the belt pulleys 120 operates through a transmission mechanism 121 and transmission belt 122; transmission belt 122 being operated by means of a grooved pulley 123 fixed to the main shaft 6.

Above the rotary feeding devices thus formed, fibre collecting devices 124, numbering the same as the feeding apparatus, are provided.

In each fibre collecting device, an arrangement to stop the spools is provided. To explain the construction of the fibre collecting device and operation of the spool stopping arrangement reference is had to Fig. 11 and Fig. 12. A supporting piece 125 is formed above the base plate 103; and the top thereof is formed into a bent plate 127 having a hole 126. Adjoining the hole, a slot 128 is cut through the plate and under the bent plate a lever 129 is fitted on an axle 130, the end of which forms fibre collecting member 131. On the other end of lever 129, a projection piece 132 is formed; and to the axle 130 a thread guiding wheel 133 is fitted. A reciprocating rod 135, fitted with engaging projection 134 is inserted in the hole 126. The lower end of the projection 134, rests on the projection 132 of the lever 129; and to the lower end of sustaining plate 125, a lever 136 is fastened and made capable of pushing up the vertical reciprocating bar 135. In the middle portion of the reciprocating rod 135, a thread guiding wheel 137 is fixed, so as to move freely up and down, and the upper portion of the rod is sustained by sustaining plate 138. At the upper end of the rod, a reel 140 fitted with pulley 139 is provided, so as to be free to perform up and down motion. In the thread collecting device 124 thus formed and spool stopping arrangement, threads gradually coming up from rotary feeding devices, go round the spools through thread collecting member 131. In case knots are formed in threads, they press against thread collecting device 124, causing lever 129 to tilt up about the axle 130; thus the reciprocating rod 135 sustained by the projection 132 of the lever 129 comes down; and pulley 139 connected to the rod also comes down, presses against the circumference 141 of the spool 48, and stops the rotation of the spool. When knots, loops and nibs are removed, the lever 136 is operated to push up the lower end of the reciprocating rod 135 and thus the former position is resumed and the rotation of reeling spools is resumed.

Under reeling spools 48, steam pipes 142 and 143, Fig. 3, are laid horizontally, to dry the threads appropriately; the steam pipes 142 and 143 being connected to the main pipe 94 through a connection pipe 144, Fig. 1. A cock 145 is pro-

vided in the connection pipe and at an appropriate situation of steam main 94, a drain pipe 147 fitted with cock 146 is provided and drains off water condensed in the steam pipes.

5 The belt 118 held stretched against the rotary feeding devices 102 are moistened at their ends with water coming from water pipes 148 and 149 which are connected to the pipes 71 connected to the water main 76.

10 In Fig. 3, 150 and 151 show "kennel" devices engaging with the thread guide wheels 137 and 138; and 152 and 153 are threads to wind round reeling spools, through rotary feeding devices 102 and the thread collecting device 124.

15 In the operation of the present invention, by an appropriate means, boiled cocoons are taken to boiled cocoon storage basin 70; then utilizing the sloping plane of bottom of the basin, a proper amount of cocoons adjusted by catching the fibre ends, is preserved in the projections 60 and at the same time, made to float in the water tank 56 provided under the rotary feeding device; fibres coming off from the cocoons are made to pass through the passage hole 106 of rotary feeding devices 102; and through the thread collecting member 131 of the thread collecting device 124, the fibres are assembled by means of "kennel" device and through the thread guides 46 of the rocking bar 44, made to wind round the spools 48.

20 After these preparations are completed, the entire machine is operated; those cocoons reserved at curved parts 58 and 59 by means of projection 60, are gradually fed to rotary feeding devices; cocoons not adjusted at boiled cocoon storage basin, are taken to cocoon basket 67 suspended in the fibre catching member 61 and boiled; the cocoons, properly boiled there, are transferred to the hollow pots 63 of the fibre adjusting member, being retained in baskets; cocoons whose fibre ends are adjusted, are suspended at projections 60 also and treated in similar manner as explained above; and cocoons whose fibres have broken, are taken to the dropped cocoon storage 68. When a fair amount of cocoons has collected, the cocoons are taken to the hollow basin 61 of fibre end catching member and similarly treated there. Of the cocoons dropped into water tank 56, those which have fibre ends are directly supplied to the feeding devices and then fastened and fed for operation; in this way, cocoons to be fed to the rotary feeding devices are given constant temperature and uniform goods are produced.

25 The rotary feeding devices 102 operated by the belt 118 are fed with water at the clearance hole 112, the water being carried along with the running belt 118; and passing through the holes 111 into the clearance hole. Thus the rotation of thread passage axle 104, is smoothly done by water lubrication; fastening and feeding are done and threads are sent up.

30 When the cocoon fibres have broken during fastening and feeding operations, the fibres are taken to the embracing rod 115 and fastened there with other fibres.

35 In this way, fibres from rotary feeding devices pass to the rocking bar 44 from fibre collecting devices through "kennel" devices, where by the arrangement above explained, threads are moved to right and left and uniformly wound round spools 48. When knots, loops and nibs are formed, spools are automatically stopped by operations above explained and winding ceases.

40 The present invention comprises the construc-

tion fully explained above by which multiple thread reeling is smoothly and efficiently done at the same time; characteristic features of reeling pan, rotary fastening and feeding apparatus, automatic stopping arrangement of spools, reciprocating device of rocking bar due to special mechanism, spools provided so as to be detachable and to be operated independently by friction, spools or reeling pans and pipe arrangement for steam, water and drainage connected with them, all combine to produce goods of superior quality.

I claim:

1. In a reeling machine, a frame, reeling axles 15 rotatably mounted in the opposite sides of said frame, reeling spools carried by each of said axles, a main axle common to the reeling axles, variable speed transmission gearings connecting the main shaft with the reeling shafts for driving the latter at independently variable speeds, a rotary fibre feeding device for each spool, a reeling pan underneath the feeding devices, a stopping device for each spool operated in dependence upon the tension of the thread, reciprocating bars, thread guides carried by said 25 bars, and means for actuating said bars in dependence upon rotation of the reeling axles to guide the threads onto said spools.

2. A reeling machine as claimed in claim 1, characterized by the provision of manual means 30 for adjusting the transmission gearings for varying the speed of the reeling axles and for correspondingly varying the speed of reciprocation of said bars.

3. A reeling machine as claimed in claim 1, characterized in that said spools are frictionally fitted on said reeling axles, and means on said spools to prevent the passage of threads therebetween.

4. A reeling machine as claimed in claim 1, characterized by the provision of a driving belt common to the several fibre feeding devices on each side of the machine, and means for supplying water to said belts.

5. A reeling machine as claimed in claim 1, characterized by the provision of a driving belt common to the rotary feeding devices on each side of the machine, each of said feeding devices including a pulley engaging said belt, a vertical passageway for the thread and openings connecting the passageway with the portion of the pulley engaged by said belt.

6. A reeling machine as claimed in claim 1 characterized by the provision of a driving belt common to the rotary feeding devices on each side of the machine, each of said feeding devices including a pulley engaging said belt, a vertical passageway for the thread and openings connecting the passageway with the portion of the pulley engaged by said belt, and detachable arms carried by said pulley.

7. A reeling machine as claimed in claim 1 characterized by the provision of heating means arranged adjacent said spools.

8. A reeling machine as claimed in claim 1 characterized in that said variable speed transmission gearings each include an adjustable friction drive.

9. A reeling machine as claimed in claim 1 characterized in that said reeling spools each include a frustro-conical body formed of light metal and coated with corrosion resisting material, said body having side plates and a hollow tubular axle connecting said plates, and frictionally engaging said reeling axles, and thread guides projecting laterally of said side plates.

10. A reeling machine as claimed in claim 1 characterized in that each stopping device includes a braking member engageable with the related reeling spool, a pivoted lever normally retaining said braking member in elevated inoperative position, a thread guide carried by said lever and adapted to be actuated upon passage of a disarranged thread to tilt said lever whereby the braking member may move to operative position.

11. A reeling machine as claimed in claim 1 characterized in that each stopping device includes a braking member engageable with the related reeling spool, a pivoted lever normally retaining said braking member in elevated inoperative position, a thread guide carried by said lever and adapted to be actuated upon passage of a disarranged thread to tilt said lever whereby the braking member may move to operative position, means pivotally mounting said lever and thread guide means carried by the pivot of said lever.

12. A reeling machine as claimed in claim 1 characterized in that each of said reciprocating bars is provided with curved resilient edges having metallic inserts and movably engaged with guide rollers.

SABURO MINORIKAWA.
